Primary Examiner — Susan Moon Lee(74) *Attorney, Agent, or Firm* — Sarah Hegi Simpson; McWhorter, Cobb & Johnson, LLP(57) **CLAIM**

I claim the ornamental design for a handrail, as shown and described.

DESCRIPTION

FIG. 1 is a perspective view of a handrail showing my new design;

FIG. 2 is a side view of the handrail of FIG. 1; and,
FIG. 3 is a side view of the handrail of FIG. 1.

The broken lines in the drawings are for illustrative purposes only and form no part of the claimed design.
